UNITED STATES PATENT OFFICE.

ANDREW JOSEPH ALLARD, OF RICHMOND, VIRGINIA.

TIME-OPERATED CIRCUIT-CONTROLLING MEANS.

1,252,874.

Specification of Letters Patent.

Patented Jan. 8, 1918.

Application filed January 16, 1917. Serial No. 142,696.

To all whom it may concern:

Be it known that I, ANDREW J. ALLARD, a citizen of the United States, and a resident of Richmond, in the county of Henrico and State of Virginia, have invented certain new and useful Improvements in Time-Operated Circuit-Controlling Means; and I do hereby declare the following to be a full, clear, and exact description of the invention, such as will enable others skilled in the art to which it appertains to make and use the same.

This invention relates to improvements in time operated circuit controlling means for lighting and extinguishing electric lights, and more particularly for controlling the lighting and extinguishing of the lights on automobiles at predetermined times,—one object of the invention being to provide simple and efficient means associated with the mechanism of an automobile clock for closing the circuits at a predetermined time, of the electric lighting system, embodying the head and tail lights of an automobile and to retaining said circuits closed for a definite length of time.

A further object is to provide, in an automatic clock, means for closing lighting circuits at a predetermined time, and simple and efficient means for setting the mechanism to operate at a predetermined time.

With these and other objects in view, the invention consists in certain novel features of construction and combinations of parts as hereinafter set forth and pointed out in the claims.

In the accompanying drawings; Figure 1 is a face view of an automobile clock, with the face removed, showing an embodiment of my invention; Fig. 2 is a sectional view; Fig. 3 is a face view of the clock face; Fig. 4 is a vertical transverse section; Fig. 5 is a diagrammatical view.

1 represents a clock casing and 2 the frame in which the major portion of the mechanism is mounted. The time mechanism of the clock may be conventional in construction and transmits motion to a comparatively large spur wheel 3 mounted loosely to rotate on a spindle 4 and to move longitudinally of said spindle. This spindle carries a hand 5 to register with a dial 6 on the clock face and said dial is graduated to represent twenty four hours divided into two series of twelve hours each representing the a. m. and p. m. divisions of a day. The

spindle 4 is provided with a fixed hub 7 having a laterally projecting lug 8 and the spur wheel is provided on its outer face with a cam 9 to engage said lug. A spring arm 10 is secured at one end to the frame some distance from the spur wheel, at one side thereof and extends under said wheel and to an appreciable distance beyond the same at the opposite side thereof,—said spring having a hole intermediate of its ends for the passage of the spindle 4 and the tendency of said spring is to press the spur wheel outwardly against the hub 7 and its lug 8. The free end of the spring arm 10 is bifurcated to engage a grooved collar 11 at one end of a longitudinally movable rod 12 mounted in the framework 2. At its other end, said rod has secured thereto a plurality of electrically connected switch arms 13—14—15 to engage (under certain conditions) a plurality of contact blocks 16—17—18 secured to but electrically insulated from one of the plates of the framework 2.

A suitable source of electric energy is illustrated diagrammatically at 19 and may consist of a suitable battery located at any convenient position in the car. One pole of this battery is grounded, as shown at 20, while the other pole of said battery is connected by means of a conductor 21 with the contact block 18 of the circuit closer above described. The head lights 22, 22 of the car are connected in a circuit 23 between the contact block 16 and a grounded connection 24, while the tail light 25 of the car is connected in a circuit 26 between the contact block 17 of the circuit closer and a grounded connection 27.

It will be seen that when the rod 12 rises to cause the switch arms to engage the contact blocks of the circuit closer, two grounded circuits included in parallel with the source of electrical supply and including the head and tail lamps, respectively, will be closed, thus causing said lamps to be lighted.

When the rod 12 is free to rise, it will be forced upwardly by the action of a spring 28 encircling said rod and bearing at one end against the collar 11 on said rod and at the other end against one of the plates of the framework 2.

The movements of the rod 12 to close the circuits of the head and tail lights of the car and to open said circuits at predetermined times, are controlled by the clock mecha-

nism, through the medium of the spur wheel 3 and its cam 9 coöperating with the lug 8 carried by the spindle 4, and the movements of said rod 12 to effect the closing or the 5 opening of the lighting circuits at predetermined times are controlled by the position at which the lug 8 may be set relatively to the cam 9 on the spur wheel 3, and said cam is of such length as to cause the lighting 10 circuits to be maintained open during daylight hours. The lug 8 may be so set (as indicated on the dial 6) that the cam 9 will ride past the lug 8 at a predetermined time (say 6 o'clock p. m.) and thus permit the 15 spur wheel to move longitudinally on the spindle and the spring arm 10 to release the circuit closer and effect the closing of the lighting circuits. The distance on the face of the spur wheel, between the ends of the 20 cam 9 is such that the lighting circuits will be maintained closed for approximately twelve hours,—at the expiration of which time, the cam 9 will ride under the lug 8 and cause such movement of the rod 12 as will 25 open the circuit closer and thus extinguish the lights.

Means are provided however, whereby the lighting circuit may be opened at the will of the operator so that the lights may be 30 extinguished when the car is run into the garage at a time during the night earlier than the time at which the mechanism may be set to open the circuit closer automatically. Such means may consist of a manually 35 operable switch 29 which may be conveniently located in the circuit 21 as shown in Fig. 5. In applying this switch to the clock, the switch arm 29 may be pivotally mounted between its ends on the interior 40 wall of the casing 1 and contact blocks 30—30 may be also secured to but insulated from said casing in position to be electrically connected by the switch arm 29,—said contact blocks being included in the circuit 45 21. A hand lever 32 is pivotally mounted on the flange 33 of the casing and connected with the pivoted switch arm 29 for operating the latter.

To provide simple and efficient means for 50 setting the hand 5 on the dial 6 and consequently setting the lug 8 carried by the spindle 4 relatively to the cam 9 on the spur wheel 3, the devices now to be described may be employed:

55 A pinion 34 is secured to the spindle 4 and is adapted to receive motion (under certain conditions as hereinafter described) from a pinion 35 carried by a spindle 36,—the latter being mounted in the framework 60 in a manner to permit it to be moved longitudinally and to the upper end of this spindle, a pinion 37 is secured and receives motion (under certain conditions) from an annular rack 38 carried by a ring 39 mounted 65 on the casing 1 and having a knurled pe-

riphery to permit it to be readily turned by the operator. A spring 40 surrounding the spindle 36 serves to normally retain the spindle in its inner or lower position with the pinions 35 and 37 normally out of mesh 70 with the pinion 34 and the rack 38 respectively. A cam flange or disk 41 is provided on the spindle 36 and a manually operable lever 42 is mounted on the casing and formed with a toe 43 to engage the cam 75 disk or flange 41 and cause the spindle 36 to be moved longitudinally so as to move the pinion 35 into mesh with the pinion 34 and the pinion 37 into mesh with the rack 38. If the ring 39 be now turned, motion 80 will be imparted to the spindle 36 and the lug 8 on said spindle may be set relatively to the cam 9 on the spur wheel 4, so that the circuit closer will be operated at any predetermined time, as indicated on the dial 85 6 when the spindle 36 is turned as above described. The lever 42 will be maintained in its normal position with its toe 43 out of engagement with the cam flange or disk 41, by the action of a spring 44. 90

The ring 39 and its annular rack may also be utilized to operate the winding mechanism and for setting the hands of the clock, but as these winding and setting devices form no essential part of my present invention, specific description of the same herein is not necessary. 95

In the modified circuit closing means shown in Fig. 6, the spring arm 10 is utilized in forming one member of a circuit closer, the other member of the latter consisting of an arm 45,—both the arm 45 and the spring arm 10 being insulated from the framework and the spring arm 10 being also insulated from the spindle 4. 100

In the arrangement shown in Fig. 7, the spindle 3 with its lug 8, and the spur wheel 4 are utilized as the circuit closing means. With this construction, the spindle 3 is insulated from the casing and from the spur wheel 110 4 and the cam 9 is insulated from the wheel 4 or said cam may be made of insulating material. The spring arm 10 makes electrical contact with the spur wheel 4 and one circuit terminal is connected with said spring arm, while the other terminal is connected with the spindle 3. With such construction, it is apparent that when the lug 8 is in contact with the metal of the spur wheel, the circuit will be closed and that 115 when said lug is in engagement with the insulated cam on said wheel, the circuit will be open.

Various slight changes might be made in the details of construction of my invention, 120 without departing from the spirit thereof or limiting its scope and hence I do not wish to restrict myself to the precise details herein set forth.

Having fully described my invention, 130

what I claim as new and desire to secure by Letters-Patent, is:—

1. A device of the character described, comprising the casing and frame of a time mechanism, a rod mounted to move longitudinally in said frame and adapted to be moved in one direction by the operation of the time mechanism, a spring for moving said rod in the other direction, contact arms carried by said rod, contact blocks secured to the frame in position to coöperate with said contact arms, an electric circuit including lamps connected with said contact blocks, electrically separated switch blocks carried by said casing and connected in said circuit, and a manually operable switch lever mounted on said casing and coöperable with said switch blocks for opening or closing said circuit.
2. A device of the character described comprising the casing of a time mechanism, a casing therefor, a spur wheel to be operated by the time mechanism and carrying a cam, a spindle on which said wheel is movable longitudinally, a lug on said spindle to coöperate with said cam, and circuit closing means controlled by the movements of said wheel longitudinally on the spindle, a manually operable ring mounted on the casing and provided with an annular rack, a 30 pinion carried by said spindle, a longitudinally movable spindle, pinions on said longitudinally movable spindle normally out of mesh with said first mentioned pinion and annular rack respectively, a cam 35 flange on said longitudinally movable spindle, and a lever mounted on the casing and having a toe thereon to engage said cam flange to move the pinions on said spindle simultaneously into mesh with the first- 40 mentioned pinion and the rack respectively whereby the first-mentioned spindle may be turned to set the lug thereon relatively to the cam on the spur wheel, when the manually operated ring is turned, and a spring 45 for moving said longitudinally movable spindle to disengage the pinions thereon from the first mentioned pinion and the rack.

In testimony whereof, I have signed this 50 specification in the presence of two subscribing witnesses.

ANDREW JOSEPH ALLARD.
